UNITED STATES PATENT OFFICE.

GEORGE B. STACK, OF SACRAMENTO, CALIFORNIA.

DESIGN FOR A CASING FOR SOAP-POWDER-DISPENSING APPARATUS.

41,789.

Specification for Design.

Patented Sept. 19, 1911.

Application filed June 13, 1911. Serial No. 632,957. Term of patent 7 years.

To all whom it may concern:

Be it known that I, GEORGE B. STACK, a citizen of the United States, residing at Sacramento, in the county of Sacramento and State of California, have invented a new, original, and ornamental Design for a Casing for Soap-Powder-Dispensing Apparatus, of which the following is a specification, reference being had to the accompanying drawing, forming part thereof.

The figure is a side view of a casing for

soap powder dispensing apparatus, showing my new design.

I claim:

The ornamental design for a casing for soap powder dispensing apparatus, as shown.

GEORGE B. STACK.

Witnesses:

EMIL BAYER,
M. S. WAHRHAFTIG.
